EXTRUDED STRAIGHT EAVE CONNECTOR MEMBER

Irvine Kimmel, 2375 NW. 75th St.,
Miami, Fla. 33155

Filed Aug. 17, 1970, Ser. No. 24,542

Term of patent 14 years

Int. Cl. D25—03

U.S. Cl. D13—1

FIG. 1

FIG. 3

FIG. 2

FIG. 4

FIG. 5

FIG. 1 is a perspective view of an extruded straight eave connector member showing my new design.

FIG. 2 is an end view.

FIGS. 3 and 4 are side elevational views thereof.

FIG. 5 is a bottom plan view.

I claim:

The ornamental design for an extruded straight eave connector member, substantially as shown.
